(57) **CLAIM**

The ornamental design for augmented reality smartglasses, as shown and described.

DESCRIPTION

1. Augmented reality smartglasses

1.1 : Perspective

1.2 : Front

1.3 : Back

1.4 : Top

1.5 : Bottom

1.6 : Left

1.7 : Right

1.8 : Perspective

1.9 : Bottom

The broken lines in the Figures 1.8 and 1.9 depict environment that forms NO part of the claimed design.
